UNITED STATES PATENT OFFICE

CHARLES B. DYGERT AND CORAL T. VAN ALSTINE, OF ILLION, NEW YORK, ASSIGNEES
TO REMINGTON ARMS COMPANY, INC., A CORPORATION OF DELAWARE

FIREARM

Application filed January 4, 1929. Serial No. 330,197.

The present invention relates to improvements in firearms, especially of the type set forth in co-pending application Serial No. 310,305, filed by Crawford C. Loomis, October 4, 1928, wherein is disclosed a firearm of the single-shot breech-loading type. Manual operation of the breech block, after firing, causes actuation of an extractor member which withdraws the fired shell from the 10 breech to a position for manual removal.

It is an object of the present invention to provide an improved mechanism actuated by movement of the breech block to not only extract the fired shell but also to eject the 15 same clear of the firearm, thus leaving the breech open for a fresh cartridge to be inserted therein.

It is a further object of our invention to provide, in a firearm having a predetermined 20 required sequence of operations for its breech closing mechanism, an ejector device, the operation of which cooperates with the required sequence of operations of the breech closing mechanism, in order to insure a high 25 degree of safety to the operator of the firearm.

It is a further object of the invention to provide in a firearm having a removable barrel a combined shell extractor and ejector 30 mechanism which, on removal of the barrel, will not be deranged, but nevertheless will be accessible for cleaning and lubricating.

With these and other objects in view the invention consists in the novel combinations 35 and arrangements of parts as illustrated by the preferred embodiment described in the following specification of which the accompanying drawings form a part.

In the drawings:

Fig. 1 is a fragmentary longitudinal elevation in section of our improved firearm showing the parts in the fired position.

Fig. 2 is a plan view of the receiver portion with the barrel removed.

Fig. 3 is an inverted plan view of the rear end of the barrel showing a portion of the extractor-ejector mechanism carried thereby.

Fig. 4 is an enlarged fragmentary sectional elevation of the receiver and the firing mech-

anism and extractor-ejector mechanism housed therein.

Fig. 5 is an enlarged fragmentary sectional elevation of the receiver showing the relation of the parts after the ejection of a fired shell, and with the breech open ready for the reception of a fresh cartridge. 55

Fig. 6 is a transverse section through line 6-6 of Fig. 3.

Fig. 7 is an end view, taken as indicated 60 by the line 7-7 of Fig. 3.

With reference to the accompanying drawings, the numeral 10 designates a barrel detachably connected to forearm 11 by means of screw 12 passing through the forearm and into the lower portion of the barrel. The barrel is detachably mounted by means of a take-down mechanism on a receiver portion 13 which houses the firing mechanism. This take-down mechanism comprises a plug 14, 70 tapped into the lower portion of the barrel, and counterbored and threaded to receive a take-down screw 15 which passes through an aperture in the receiver. The usual stock 16 is attached by a tang screw 17 to the receiver. 75

Within the receiver a breech block 18 is pivoted at 19. The breech block is formed with an upstanding portion 20 which houses a firing pin 21. A hammer 22 is pivoted at 23 and a trigger 24 is pivoted at 25. Spring 80 pressed plunger 27 in the trigger piece being urged against an abutment 26 in the receiver wall tends to hold a nose portion 28 of the trigger in an elevated or hammer engaging position (Fig. 5). A notch 29 is provided 85 in the hammer to be engaged by the trigger nose to hold the hammer in a full-cocked position. A notch 30, somewhat deeper and shaped to engage and lock the trigger when the hammer is in a half-cocked position, is 90 also provided in the hammer.

As more fully explained in the co-pending application Serial No. 310,305, referred to above, the loading and cocking operations take place in a definite sequence in order to insure a high degree of safety to the operator of the firearm. If, after firing, the hammer be retracted to the full-cocked position (not illustrated), shoulder 32 on the lower 95 forward portion of the hammer will be raised 100

to such a position as to form an abutment for a heel portion 31 of the breech block, and thereby prevent the breech block from swinging downward far enough to expose the breech for inserting a cartridge therein. The half-cocked position only of the hammer will permit the breech block to be lowered enough to clear the breech for loading (Fig. 5). Depression of the breech block is afforded by manipulation of knurled finger piece 33 mounted at the side of the breech block by means of an integral shank which extends transversely through the breech block, the shank also serving to limit the movement of firing pin 21 by its position in an elongated depression in the top of the pin.

In the fired position of the hammer, as shown in Fig. 4 a shoulder portion 34, whose surface is arcuate and concentric with the hammer pivot 23, will engage the heel portion of the breech block in line with the pivot 23 to securely lock the breech block in breech closing position at the time of firing.

A spring 35 serves as a hammer spring to urge the hammer into its fired position (Fig. 4). This spring 35 is supported by spring pilots 36 and 37 telescopically receiving each other, the spring 35 bearing on a shoulder portion on each of the pilots, as clearly shown. One of the spring pilots bears on hammer 22, and the other pilot bears on the breech block 18. Thus, the spring 35 serves not only as a hammer spring but also to yieldingly hold the breech block in breech closed position. It will be seen in Fig. 5 that the spring 35 bearing on breech block 18 exerts its force below the pivot 19, thereby yieldingly holding the breech block in its lowermost position. By shifting the line of thrust of said spring from the position shown in Fig. 5 to the position shown in Fig. 4, or vice versa, the breech block may be held in either open position or closed position of the breech.

Manual depression of the breech block causes operation of our improved extractor-ejector mechanism, which mechanism will now be described. A combined extractor-ejector member, as shown at 40, riding in a groove or channel 41 formed in the lower rear portion of the barrel, is stabilized by longitudinal guides 38 integral with the extractor member, which also ride in recesses formed in the barrel, as shown in Fig. 7. The member 40 is urged rearwardly by spring 42, which spring bears against plug 14 at its forward end. A transverse pin 43 positioned in an elongated recess 44 in the lower portion of member 40 retains the member in its guide channel. At the rear portion of member 40 is formed a projecting lip 45 adapted to engage the rim of a cartridge shell. At the lower side of member 40 are formed two downwardly projecting lugs 46 and 47 which are adapted to be engaged by members on the breech block as will be explained hereinafter.

Breech block 18 is cut away as at 48 to provide a space for a sear member 50 to move vertically through a limited arc around a pivot 49. A spring 51, seating in a recess 39 in the breech block, engages the lower forward portion of the sear member 50 to urge the same upward into engagement with a stop pin 52. The sear member 50 at its forward portion is cut away to form a bearing seat for lug 47 of the extractor member. At a point in the downward movement of the breech block, the member 50 will disengage the lug 47, and during this movement, in order to prevent binding of the parts and to insure a smooth action, the member 50 is permitted to move slightly about pivot 49 and against the resilient influence of spring 51. A transverse pin 53 is provided in the recess 48 of the breech block for movement with the breech block, and is positioned to be engaged by lugs 46 and 47 to limit and control the movements of the extractor member.

The operation of our improved extractor-ejector mechanism is as follows:

Assume that in Fig. 4 the shell in the breech has been fired and is now ready to be removed from the barrel. By bringing the hammer to a half-cocked position, as shown in Fig. 5, the breech may be depressed by pressing down on finger piece 33. During the first part of this downward movement (referring to Fig. 4) the pin 53 and sear member 50 will be caused to move in an arcuate path about pivot 19. The engagement of pin 53 with lug 47 will cause the extractor member 40 to be positively moved rearward, thus extracting the shell from the breech. As the breech is moved further downward, the sear member 50 moving in an arcuate path about pivot 19 and restrained in its upward movement by pin 52 from the pressure of spring 51 will tend to move away from lug 47. At a point in the downward movement of the breech block it will be seen that a position will be reached where the sear 50 will be disengaged from the lug 47, and will suddenly release the same causing the extractor member 40 to snap suddenly rearward under the pressure of its spring 42 until lug 46 strikes sharply against pin 53. The inertia of the shell, being carried by the extractor, will then cause it to fly clear of the firearm.

The position of the breech block at which sear 50 will release its hold upon lug 47 will occur after the breech block has been rocked to a position just below the point where further movement of the breech block would be limited if the hammer were in full-cocked position, as heretofore explained. Thus, ejection of the shell can take place only in the half-cocked position of the hammer. This insures that the required sequence of operations previously explained will not disturb but will cooperate with the

operation of the improved extractor-ejector mechanism.

On returning the breech block to its upward position, it will be seen that pin 53 bearing against lug 46 will cause the extractor member to begin its return movement, and the engagement of the breech block with the extended end of the extractor member 40 will cause the extractor member to be 5 fully returned to the position of Fig. 4, whereupon sear 50, after yielding slightly under the pressure of spring 51 to permit lug 47 to pass, will re-engage said lug, as in Fig. 4.

It will be understood that various modifications and changes in the shape, size, construction and arrangement of some or all of the parts of this invention may be made without departing from the spirit of the invention 15 as hereinafter claimed.

What we claim is:

1. In an ejector mechanism for firearms, in combination, a receiver, a firing chamber, a pivoted breech block mounted in said receiver movable to close said chamber, an ejector member slidable to move from shell engaging position in the breech to a shell ejecting position, means whereby movement of said breech block will positively exert an extracting movement to said ejector member, and means controlled by further movement of said breech block to impart a shell ejecting movement to said ejector member.

2. In an ejector mechanism for firearms, in combination, a receiver, a firing chamber, a breech block pivoted in said receiver and movable to close said chamber, an ejector member movable from a position adjacent said chamber to a shell ejecting position, means, whereby initial movement of said breech block will impart a shell extracting movement to said ejector member, and other means controlled by further movement of said breech block to impart a shell ejecting movement to said ejector member.

3. In an ejector mechanism for firearms, in combination, a firing chamber, a receiver, a breech block pivoted in said receiver, an ejector member movable from a retracted position to a shell ejecting position, means carried by said breech block engaging said ejector to restrain the same from moving to shell ejecting position, said engaging means being releasable at a predetermined point in the movement of said breech block, and additional means carried by the breech block engageable with the ejector member to positively impart a shell-extracting movement to said ejector member.

4. In an ejector mechanism for firearms, in combination, a firing chamber, a breech block pivoted to close and open said firing chamber, an ejector member, means carried by said breech block engageable with said 50 ejector member and movable to release the

ejector member during the opening movement of said breech block, other means carried by the breech block engageable with the ejector member to impart an extracting movement to said ejector member, the said last-mentioned means being also engageable with the ejector member to stop the movement of the ejector member after release by the first-mentioned means.

5. In a firearm, in combination, a firing chamber, a pivoted breech block, a hammer, a trigger adapted to hold said hammer in either of two positions, an ejector mechanism operable to extract and eject a shell, means preventing operation of said ejector mechanism when said hammer is held in one position by said trigger, while permitting operation of said ejector mechanism when said hammer is held in the other of said positions.

6. In a firearm, in combination, a firing chamber, a breech block, a hammer, a trigger adapted to hold said hammer in either of two positions, means whereby the breech block obstructs the chamber when the hammer is held in one of its positions, the breech block being permitted to clear the breech in the other held position of the hammer, an ejector member movable to extract and eject a shell means whereby the ejector member is prevented from moving for shell extraction and ejection when the hammer is held in the first-mentioned position, the said last-mentioned means permitting movement of the ejector member for shell extraction and ejection when the hammer is in its other held position.

7. In a firearm, in combination with a receiver and a breech block pivoted therein, an ejector mechanism comprising an ejector member movable from a retracted position to a rearward shell ejecting position, said ejector having two engaging means, a device carried by said breech block engageable with the first of said engaging means to positively move said ejector member away from its retracted position, said device serving also as a limiting stop to be engaged by the second engaging means at the shell ejecting position of the ejector member.

8. In a firearm, in combination, a firing chamber, a receiver, a breech block pivoted in said receiver, an ejector member movable relative to said receiver, means for positively moving said member to extract a shell, resilient means for imparting a shell ejecting movement to said member, and a member pivoted on said breech block and engaging said ejector member to control the movement thereof.

9. In a firearm, in combination, a firing chamber, a receiver, a breech block pivoted in said receiver, an ejector member movable relative to said receiver, means for positively moving said member to extract a shell, resilient means for imparting a shell ejecting

movement to said member, and means carried by said breech block for controlling the movement of said ejector member.

10. In a firearm, in combination, a firing chamber, a receiver, a breech block pivotally mounted for movement in said receiver, a hammer, a trigger adapted to hold said hammer in either a safety position or a firing position, means interposed between said breech block and said hammer permitting full movement of the breech block when said hammer is in safety position but restricting said movement when the hammer is removed from said position, an ejector member movable to extract and eject a shell, devices controlled by the full movement of the breech block to operate the ejector member whereby shell extraction and ejection are prevented when the hammer is removed from its safety position, and permitted when the hammer is in safety position.

11. In a firearm, in combination, a firing chamber, a receiver, a breech block pivoted in said receiver for movement therein, an ejector member movable relative to said receiver, means for positively moving said member to extract a shell, resilient means for imparting a shell ejecting movement to said member, and means carried by said breech block to restrain said member from shell ejecting movement until released by movement of said breech block.

12. In a firearm, in combination, a firing chamber, a receiver, a breech block pivoted in said receiver for movement therein, an ejector member movable relative to said receiver, means for positively moving said member to extract a shell, resilient means for imparting a shell ejecting movement to said member, and a member pivoted on said breech block and engaging said ejector member to restrain said member from shell ejecting movement until released by movement of said breech block.

13. In a firearm, in combination, a firing chamber, a receiver, a breech block pivoted in said receiver for movement therein, an ejector member movable relative to said receiver, means carried by the breech block engaging said member for positively imparting a shell extracting movement thereto, resilient means for imparting a shell ejecting movement to said member, and means carried by said breech block to restrain said member from shell ejecting movement until released by movement of said breech block.

14. In a firearm, in combination, a firing chamber, a receiver, a breech block pivoted in said receiver for movement therein, an ejector member movable relative to said receiver, means carried by said breech block engaging said member for positively imparting a shell extracting movement to said member, resilient means for imparting a shell ejecting movement to said member, and a member

pivoted on said breech block and engaging said ejector member to restrain said ejector member from shell ejecting movement until released by movement of said breech block.

15. In a firearm, in combination, a firing chamber, a receiver, a breech block pivoted in said receiver, an ejector member movable relative to said receiver, two depending lugs carried by said member, a stop element carried by said breech block and riding between said lugs to limit the movement of said member, a sear member pivotally mounted on said breech block and engaging one of said lugs, said sear being releasable from said lug to permit a shell ejecting movement of said ejector member.

16. In a firearm, in combination, a firing chamber, a receiver, a breech block pivoted in said receiver, an ejector member movable relative to said receiver, a lug carried by said member, a sear member pivotally mounted on said breech block and engaging said lug, said sear being releasable from said lug to permit a shell ejecting movement of said ejector member, and resilient means carried by said breech block normally urging said sear toward its lug engaging position.

17. In a firearm, in combination, a firing chamber, a receiver, a breech block pivoted in said receiver, an ejector member movable relative to said receiver, a projection formed on said ejector member, means carried by said breech block engageable with said projection to impart an extracting movement to said member on movement of said breech block, additional means carried by said breech block engageable with said projection to restrain said member from ejecting movement and to release the same on further movement of the breech block.

18. In a firearm, in combination, a firing chamber, a receiver, a breech block pivoted in said receiver, an ejector member movable relative to said receiver, a projection formed on said ejector member, means carried by said breech block engageable with said projection to impart an extracting movement to said member on movement of said breech block, a sear pivoted on said breech block and engaging said projection to restrain said member from ejecting movement and to release the same on further movement of the breech block.
